METHOD OF AND MEANS FOR PERMANENTLY WAVING HAIR

Original application filed January 21, 1932, Serial No. 587,890. Divided and this application filed September 22, 1932. Serial No. 634,290.

This invention relates to that class of hair waving in which a so-called permanent wave is imparted to a pre-formed tress of hair by subjecting the tress to the action of a heating chemical, such as calcium oxide, which, when moistened, will of itself generate sufficient heat to impart a permanent wave to the said tress.

This invention comprises a novel method of 10 and a novel means for controlling the development of the heat generated by the self heating chemical wherein certain materials are used to extend the development of the heat over a longer period of time than could 15 be done by the heating chemical itself.

I have found that the development of the heat may be extended successfully over a considerable period of time by combining with the heating chemical a diluent, such as sand. 20 I have also found that the development of the heat may be extended successfully over a considerable period of time by combining with the heating chemical a substance, as for instance an ammonia compound which would 25 emit a volatile gas, thereby removing the heat and keeping the temperature down.

It is to be understood that the heating chemical may be used in its dry powdered state or that it may be pressed into easily 30 friable cakes, in which case a suitable binder, such as dry glycerin, etc. may be used.

An example of a hair waving pad embodying my invention is represented in the accompanying drawing in which:

35 Fig. 1 represents an inside plan view of the pad in its unwrapped condition, the inner absorbent sheet being shown at the side of the pad and the inner wrapper sheet being shown unfolded;

40 Fig. 2 represents an inside plan view of the pad in its unwrapped condition after the inner wrapper flap has been perforated and the inner face of the chemical containing envelope has been perforated, the inner absorbent sheet being interposed between the inner face of the heating chemical containing envelope and the inner wrapper flap;

45 Fig. 3 represents a side view of the pad wrapped around a wound tress as in use; and

Fig. 4 represents a longitudinal central section through the wrapped pad.

The outer wrapper of the hair waving pad is denoted by 1 and is preferably made of non-absorbent material, as for instance paper. 55 The inner wrapper is denoted by 2 and is preferably made of metal foil. This inner wrapper is provided with a foldable flap 3. An envelope 4 composed of a perforable impervious material, such as metal foil, is attached to the inner face of the inner wrapper 60 2, which envelope contains a heating chemical, such as calcium oxide in powdered form, which chemical, when moistened, will of itself generate sufficient heat to impart a 65 so called permanent wave to a pre-formed tress when enclosed within the pad.

An inner removable sheet 5 of absorbent material, such as cotton fabric is arranged to be moistened and inserted between the flap 3 70 and the envelope 4 after the inner face of the envelope 4 and the folded over flap 3 of the inner wrapper have been perforated. The pressing of the flap back into place will squeeze the moisture from the wetted inner 75 sheet into the envelope containing the heating chemical.

In practice, the tress 6 is wound as usual around a mandrel 7. The tress may be moistened either before or after it is wound, by 80 a suitable waving solution, such for instance as an ammonia solution. The inner face of the impervious envelope 4 containing the hair waving chemical is perforated as shown at 8, and the folded over flap 3 of the inner wrapper 85 may be perforated at the same time as shown at 9. The inner sheet 5 is moistened by water or by a suitable hair waving solution, such as that used for moistening the tress 6.

The self heating chemical within the envelope may be treated to produce the results hereinbefore set forth.

The pad is then wrapped around the pre-formed tress and is preferably secured in position at the scalp end of the tress by a suitable scalp protecting guard of well known or approved form, such for instance as the self locking guard 10 shown in the accompanying drawing. The outer end of the pad may be secured around the mandrel 7, as for 100

instance by twisting the outer wrapper of the pad around the same. The exothermic action starts at once because of the application of moisture by the wetted inner sheet 5 of the 5 pad to the self heating chemical through the perforations in the inner face of the impervious envelope. A regulable heat is then set up within the pad in order to impart a so called permanent wave to the pre-formed tress with- 10 out requiring application of heat from an outside source. It will be seen that the outside wrapper of the pad serves to confine the heat to a large extent within the pad, the steam generated by the combination of the 15 treating solution with the chemical being permitted to escape through the crimped outer end of the outer wrapper.

This application is a division of my co-pending application filed January 21, 1932, 20 Serial No. 587,890, entitled Method of and means for permanently waving hair.

The method of and means for extending the development of the heat over a considerable period of time by combining a suitable medium with the moistening medium which was disclosed and claimed herein now forms the subject matter of my divisional application filed the 12th day of November, 1932, its serial number being 642,359.

30 What I claim is:

1. Imparting a permanent wave to hair by subjecting the hair to heat generated by the reaction of an exothermic material with a moistening medium, the natural development 35 of the heat being extended over a considerable period of time without raising its temperature, by combining a suitable medium with the exothermic material.

2. Imparting a permanent wave to hair by 40 subjecting the hair to heat generated by the reaction of an exothermic material with a moistening medium, the natural development of the heat being extended over a considerable period of time without raising its tem- 45 perature, by combining a diluent with the exothermic material.

3. Imparting a permanent wave to hair by 50 subjecting the hair to heat generated by the reaction of an exothermic material with a moistening medium, the development of the heat being extended over a considerable period of time by combining sand with the 55 exothermic material.

4. Imparting a permanent wave to hair by 60 subjecting the hair to heat generated by the reaction of an exothermic material with a moistening medium, the natural development of the heat being extended over a considerable period of time without raising its tem- 65 perature, by combining a salt with the exothermic material.

5. Imparting a permanent wave to hair by 65 subjecting the hair to heat generated by the reaction of an exothermic material with a moistening medium, the development of the

heat being extended over a considerable period of time by combining ammonium sulphate with the exothermic material.

6. Imparting a permanent wave to hair by 70 subjecting the hair to heat generated by the reaction of an exothermic material with a moistening medium, the development of the heat being extended over a considerable period of time by combining an ammonia compound which will emit a volatile gas with the exothermic material.

7. Means for waving hair including a 75 chemical which, when moistened, will generate sufficient heat to impart a permanent wave to the hair, a material being combined with said heating chemical for extending the natural development of the heat over a considerable period of time without raising its 80 temperature.

8. Means for waving hair including a 85 chemical which, when moistened, will generate sufficient heat to impart a permanent wave to the hair, a diluent being combined with the heating chemical for extending the natural development of the heat over a considerable period of time without raising its 90 temperature.

9. Means for waving hair including a 95 chemical which, when moistened, will generate sufficient heat to impart a permanent wave to the hair, sand being combined with the heating chemical for extending the development of the heat over a considerable period of time.

10. Means for waving hair including a 100 chemical which, when moistened, will generate sufficient heat to impart a permanent wave to the hair, a salt being combined with said heating chemical for extending the natural development of the heat over a considerable period of time without raising its 105 temperature.

11. Means for waving hair including a 110 chemical which, when moistened, will generate sufficient heat to impart a permanent wave to the hair, ammonium sulphate being combined with said heating chemical for extending the development of the heat over a considerable period of time.

In testimony, that I claim the foregoing as 1 my invention, I have signed my name this 19th day of September, 1932.

RALPH L. EVANS.
